UNITED STATES PATENT OFFICE.

DON L. HARFORD, OF DES MOINES, IOWA.

NEWSPAPER-ASSEMBLING MACHINE.

Application filed April 13, 1922. Serial No. 552,275.

To all whom it may concern:

Be it known that I, DON L. HARFORD, a citizen of the United States, and a resident of Des Moines, in the county of Polk and 5 State of Iowa, have invented a certain new and useful Newspaper-Assembling Machine, of which the following is a specification.

An object of my invention is to provide a machine of simple, durable and inexpensive 10 construction, for assembling the different sections of a newspaper, or similar printed matter, into one complete whole.

A further object is to provide such a machine wherein the sections are separated 15 in piles with their folds disposed in the same directions, and wherein the open edge of the papers will be raised for permitting the insertion of the section to be inserted.

A further object is to provide such a machine wherein the inserted sections are carried by means of lugs fixed to horizontally moving chains from one pile of sections to the pile of sections in which they are inserted. 20

25 A further object is to provide a machine in which the lifting of the free edges of the sections is accomplished by means of suction operated hands.

With these and other objects in view my 30 invention consists in the construction, arrangement and combination of the various parts of my device, whereby the objects contemplated are attained, as hereinafter more fully set forth, pointed out in my claims, and illustrated in the accompanying drawings, in which:

Figure 1 is a perspective view of my machine, showing one of the newspaper sections in the process of being conveyed into 40 the inside of another section.

Figure 2 is a detail view of the raising mechanism hereinbefore referred to, taken on the line 2—2.

Figure 3 is a detail sectional view of the 45 raising mechanism taken on the line 3—3 of Figure 1.

Figure 4 is a detail view of a portion of my machine not shown in Figure 1, taken as indicated by the line 4—4 of Figure 1.

50 Figure 5 is a detail view of another portion of my machine not shown in Figure 1, taken as indicated by the line 5—5 of Figure 1.

55 Figure 6 is a detail, perspective view of a portion of one of the raising fingers.

It is well known that in the printing

of newspapers the different sections of the paper are printed separately, sometimes on different machines, and these sections put together, to form complete newspapers, by 60 men known as stuffers, who insert the inner sections into the outer sections by hand. This is a long and tedious process and my improved machine contemplates the inserting of the sections at a very high rate of 65 speed.

In Figure 1, I have shown a perspective view of the machine, the frame of which I have indicated by the numeral 10. The frame 10 which forms what I shall term 70 the forward end of the machine, supports the driving mechanism and part of the inserting mechanism hereinafter described.

The frame 10 has its rear end open and has thereon flanges 11. An auxiliary frame 75 12 is bolted to the frame 10 by means of flanges 13 coacting with the flanges 11. The frame 12 supports the mechanism for conveying the inner sheets to the outer sheets which are supported within the frame 10. 80 Where it is desired to insert several sections within one section, other frames similar to the frame 12, may be added to the machine in order to accomplish this result.

Supported on the outside of the frame 85 10 is a gear 14 on a shaft 15, which may be connected with suitable drive mechanism (not shown). The gear 14 meshes with gears 16 and 17. Meshing with the gear 17 is a gear 18 on a shaft 19 running through 90 the machine from side to side. On the shaft 19 are a pair of sprocket wheels 20. Supported in the rear end of the frame 12 is a shaft 21 which supports a pair of sprocket wheels 20 aligned with the sprockets 95 22. Below the sprockets 22 are a similar set of sprockets 23 and below the sprockets 20 are a pair of sprockets 24. Chains 25 pass around the sprockets 20 and around the sprockets 24, 23, and 22, respectively, 100 which latter sprockets serve as idlers or sprockets.

On the chains 25 are inwardly projecting fingers or lugs 26 which are equidistantly spaced from each other. It may be 105 here mentioned that the chains 25 are spaced from each other, a distance slightly more than the height of an ordinary newspaper, so that when a pile of newspaper sections is supported between the chains, in 110 the proper position, the fingers 26 travelling forwardly in the machine, driven by

the sprockets 20, will project inwardly just enough to catch the inner edge of the fold of the newspaper section and carry the section forwardly in the machine. In order 5 to do so, the upper sheet of the newspaper must be raised and this is accomplished by a mechanism which will be later described.

I will now describe the means for supporting the piles of sections and for raising them as they are carried forwardly in 10 the machine. On the shaft 19 is a bevel gear 27. Meshing with the gear 27 is a bevel gear 28 on a shaft 29, supported in brackets 30 and 31 (see Figure 4). On the 15 shaft 29 is a gear 32 meshing with the gear 33 on a shaft 34 supported in the brackets 30 and 31. The shaft 34 extends forwardly from the machine and has on its forward end an eccentric disk 35. A pitman 36 is 20 pivoted on an eccentric pin 37. A lever 38 is pivoted to the forward portion of the machine at its lower end, and the pitman 36 is pivoted to the upper end of the lever 38 by means of a bolt 39 extending through 25 a hole 40 in the bar 38. By using several holes 40, the amount of motion transmitted to the bar 38 may be varied.

The bar 38 has a pawl 41 coacting with a ratchet 42 on a shaft 43, which extends 30 from the forward end of the machine to a bracket 43^a adjacent to the shaft 19.

On the other side of the machine from the gear 18, and fixed to the shaft 19 is a bevel gear 44 (see Figure 5). The bevel 35 gear 44 meshes with a similar gear 45 on a shaft 46, which is supported in brackets 47 and 48 on the frame 10. A gear 49 on the shaft 46 meshes with the gear 50, on the shaft 51, which extends from the bracket 47 to a bracket 52 in the rear end of the frame 12.

On the end of the shaft 51 is a ratchet mechanism 53 similar to the ratchet mechanism already described. The ratchet mechanism 53 includes a ratchet 54, which is supported on a shaft 55. The shaft 55 is journaled in the frame 12 and a bracket 56 situated at about the center of the machine. It will be noted that the shafts 55 and 43 extend longitudinally of the machine and are spaced slightly from the inside of the machine at the upper portion thereof. On the shaft 55 are reels 57, 58, 59 and 60. Ropes 61 are wrapped about the reels 57 and 58 and extend downwardly. Ropes 62 are wrapped about the reels 59, and 60 and extend downwardly to pulleys 63 and 64 mounted in the lower portion of the frame 12. From the pulleys 64 the ropes 62 extend upwardly and around the pulleys 65 mounted in the upper portion of the frame 12 on the other side from the reels 59 and 60 and thence downwardly. To the free ends of the ropes 62 and 61 there is fastened 65 a platform 66.

The ropes 61 and 62 are so arranged that when the machine is in operation, the reels 57, 58, 59, and 60 will turn in such directions as to wind up the ropes and raise the platform 66 at a rate corresponding to 70 the rate at which the newspaper sections supported on the platform 66 are carried away by the fingers 26.

It will be noted that the shaft 55 extends into the frame 10 in the rear end of which is supported a platform 67, which is operated by cables 68 wrapped about reels 69 on the shaft 55. The mechanism for raising the platform is identical with the mechanism already described. It will be noted 75 that the platforms 66 and 67 will ascend at the same rate of speed. If it is desired to lower one platform at a faster rate than the other, this may be accomplished by replacing the reels 69 with reels of slightly 80 different diameters.

I will now describe the mechanism whereby the upper sheets of the sections are raised in order to permit the entrance of 90 the fingers 26 within the sections. Mounted on the frame 10 and meshing with the gear 16 is a gear 70, which carries a bevel gear 71 in mesh with a bevel gear 72 on a shaft 73 which is journaled in bearings 74 on the frames 10 and 12 respectively.

The frames 10 and 12 have upwardly extending supports 75 which provide at their upper ends bearings for shafts 76 journaled 95 therein. On the shafts 76 are a plurality of fingers 77 which are curved downwardly. On the end of the shafts 76 are levers 78 having in their outer ends holes 79.

Mounted in the main frame of the machine adjacent to the upright members 75 are bearings 80, in which are slidably 100 mounted shafts 81. The shafts 81 have at their lower ends yokes 82 in which are pivoted connecting rods 83. On the shaft 73 are eccentric disks 84 which are received 105 in rings 85 on the ends of the connecting rods.

It will be seen from the foregoing description that when the shaft 73 is rotated, the slideable shafts 81 will be given a vertical reciprocating motion. A link 86 connects the shafts 81 with the lever 78, thus imparting reciprocating rotating motion to the shafts 76. On the upper ends of the shafts 81 are fixed arms 87 which extend inwardly to a point above a rear corner of the platforms. The arms 87 support downwardly extending arms 88 on the lower end of which are hands 89. It may be mentioned here that the purpose of the hand 89 is to lift one corner of the section of paper and that the purpose of the downwardly curved fingers 77 is to engage the under surface of the lifted sheets and raise them from one side to the other.

In order to properly describe the position

which the newspaper sections assume when placed in the machine it will first be necessary to mention the manner in which the paper is folded. During the process of printing, the paper is folded first on a vertical line and then again folded on a transverse line. I will refer to the newspaper with the number 90, this first vertical fold with the number 91, and the transverse fold 10 with the number 92.

The sections are arranged in the machine on the platforms 66 and 67 so that the fold 92 is toward the front of the machine, and the fold 91 is adjacent to the side of the 15 machine on which the hands 89 are supported.

The upper section illustrated in Figure 1, of the pile of papers on the platform 66, I will refer to with the letter A and the upper 20 section of the platform 67 with the letter B. The mechanism to which the hands 89 are attached is so arranged that the hands 89 descend upon one corner of the section when the curved fingers 77 are in their receded 25 position. The hands 89 are designed to have suction cups in their under surfaces and are connected by means of hose 93 to a suction pump 94 which is driven from the shaft 15.

As the shaft 73 rotates, the shaft 81 will 30 be lifted, the corner of the paper engaged by the hand 89 will be raised and the fingers 77 will then enter under the raised portion and continue the raising along the entire width of the sheet. It will be noted that in order 35 to accomplish this result each finger 77 is positioned a little to the rear of the adjacent fingers nearest the hand 89 as illustrated in Figure 2. This is necessary in order that each finger may raise the sheet sufficiently 40 for the next finger to enter.

When the hands 89 and the fingers 77 are at their upper limit of motion, the lugs 26 on the chain 25 will enter between the upraised portion of the paper and the lower 45 half, and will then travel forwardly until they engage the fold 92. The section A will be carried forwardly by the lugs 26 at the correct time so that it will enter under the upraised portion of the section B when the 50 mechanism acting upon the section is at its upper limit of movement.

It will be noted that while one section A is being inserted within the section B, another section A is being opened in order to 55 permit the entrance of the fingers 26.

In order to remove the sections from the lugs 26, I provide a set of conveyor belts 95, supported on shafts 96 and 97 in the main frame 10. A pinion 97^a on the end of the 60 shaft 96, meshes with the gear 16 in order to drive the conveyor belts and the gear ratio is such that the belts 95 will travel at a faster rate than the chain 25 so that the papers will be withdrawn from the lugs 26 65 before the lugs 26 start downwardly in the

machine. Conveyor belts 95 are so situated in the machine as to engage the lower surface of the newspaper sections while they are being supported by the fingers or lugs 36.

A platform 98 receives the paper sections and is lowered by reels 99 similar to the raising mechanism hereinbefore described. The reels 99 are mounted on the shaft 43 which is operated by the ratchet mechanism heretofore described. I have provided curved guide fingers 100 which catch the sections as they are discharged from the belts 95 and guide them to position on the platform 98.

It may be mentioned here that the suction applied to the hands 89 is continuous and that the paper will be gripped instantly when the hand 89 touches the section. It will be noted that two sheets are lifted as soon as the hand 89 engages the side of the paper which has the fold 91 and thus the lugs 26 are inserted between the upper and lower halves of the section. I have found that the grip produced by the suction hands is positive and that the sheets may be lifted very rapidly without danger of disengaging themselves from the hands. It will be noted that the papers are slid longitudinally in order to remove them from a hand and I have found that this is accomplished very easily. The action of the fingers 77 is positive and I have found that they never fail to enter the sections since the hands 89 lift the paper to the same height each time and the fingers 77 swing forwardly in exactly the same position.

It will be seen that the reciprocating parts are very light and have very little inertia and therefore the machine may be run at 105 a very high rate of speed without interfering with the proper operation. With the use of my improved machine, one man can do the work of ten in the same length of time and the completed papers will be much 110 more uniformly assembled.

Some changes may be made in the construction and arrangement of the parts of my improved device without departing from the essential features and purposes of my invention, and it is my intention to cover by 115 my claims any modified forms of structure or use of mechanical equivalents which may be reasonably included within their scope.

I claim as my invention:

1. In a machine for assembling folded sections of paper wherein the sections are supported in piles with their side edges adjacent and the folded portions disposed in the same direction, horizontally moving members adapted to enter each folded section, suction operated means for raising a free corner of each section and fingers adapted to enter the sections under the lifted portion and to lift the upper sheet of the 120
125
130

section to a point where the horizontally moving members may enter the sections.

2. A machine for assembling folded sections of paper, including a pair of laterally spaced horizontal chains adapted to move past the end edges of a series of piles of folded paper sections, lugs on said chains adapted to engage the inside of the folded portion of each paper means for raising a free corner of the upper sheet of each section and fingers adapted to enter the sections under the lifted portion and to lift the upper sheet to a point where the lugs will enter the sections.

15 3. In a machine for assembling folded sections of paper, wherein the sections are supported in piles with their side edges adjacent and the folded portions disposed in the same direction, horizontally moving members adapted to enter each folded section for conveying it to the next folded section, means for carrying said horizontally moving members, and means for raising the upper sheet of each folded section for allowing said horizontally moving members to enter the sections, said means comprising suction operated members adapted to lift the free corners of the upper sheets of the sections and curved fingers adapted to enter the sections under the lifted portion and to lift the upper sheet to a point where the horizontally moving members will enter the sections.

4. In a newspaper assembling machine, means for supporting a number of piles of paper sections with their side edges adjacent, means for raising a free corner of the top sheets of said sections, fingers adapted to enter the sections under the lifted portion and to further lift the entire free edge of the top sheets of the sections, and means adapted to engage the inside of the folded portion of said sections, and convey each section to the next succeeding section, for inserting each section within the upraised sheet of each succeeding section.

5. In a machine for assembling folded sections of paper wherein the sections are supported in piles with their side edges adjacent and the folded portions disposed in the same direction, horizontally moving members adapted to enter each folded section for conveying it to the next folded section, means for raising a free corner of each section and fingers adapted to enter the sections under the lifted portion and to lift the upper sheet of the section to a point where the horizontally moving members may enter the sections.

60 6. In a machine for assembling folded sections of paper, wherein the sections are supported in piles with their side edges adjacent and the folded portions disposed in the same direction, a pair of horizontal chains adapted to move past the end edges of the

sections, lugs on said chains adapted to engage the inside of the folded portion of each paper, means for raising the upper sheet of each section for allowing the lugs to enter said sections, said means comprising vertically reciprocating vertical arms, suction mouths at the lower ends thereof, means for creating a vacuum therein, said arms being arranged to descend at the proper time on the free corners of the upper sheets of the sections, and curved fingers adapted to enter the sections under the lifted portion and to lift the upper sheet to a point where the lugs will enter the section.

7. A machine for assembling folded sections of paper, wherein the sections are supported in piles with their side edges adjacent and the folded portions disposed in the same direction, horizontally moving members adapted to enter each folded section, means for raising a free corner of each section, and fingers adapted to enter the sections under the lifted portion and to lift the upper sheet of the section to a point where the horizontally moving members may enter the sections, said fingers being mounted on an oscillating shaft and spaced angularly from each other from one end of said shaft to the other.

8. In a machine for assembling folded sections of newspapers, wherein the sections are supported in piles with their side edges adjacent and the folded portions disposed in the same direction, horizontally moving members adapted to enter each folded section for carrying it to the next folded section, suction operated hands for lifting the free edge of each section, a vertically reciprocating carriage therefor, a rotating drive shaft, an eccentric disc thereon, and a pitman connecting said eccentric disc and said drive shaft for imparting vertical reciprocating motion to the carriage.

9. In a machine for assembling folded sections of newspapers, wherein the sections are supported in piles with their side edges adjacent and the folded portions disposed in the same direction, horizontally moving members adapted to enter each folded section for carrying it to the next folded section, suction operated hands for lifting the free edge of each section, a vertically reciprocating carriage therefor, a rotating drive shaft, an eccentric disk thereon, and a pitman connecting said eccentric disc and said drive shaft for imparting vertical reciprocating motion to the carriage, fingers adapted to enter the sections under the lifted portion and to lift the upper sheet of the section to a point where the horizontally moving members may enter the sections, said fingers being mounted on an oscillating shaft and spaced angularly from each other from one end of said shaft to the other, a lever on the end of said reciprocating shaft, and

a link connecting said lever to the vertically reciprocating carriage for transferring oscillating motion to the lever.

10. A machine for assembling folded sections of paper, wherein the sections are supported in piles with their side edges adjacent and the folded portions disposed in the same direction, horizontally moving members adapted to enter each folded section, 5 means for raising a free corner of each section, and fingers adapted to enter the sections under the lifted portions and to lift the upper sheet of the section to a point where the horizontally moving members may 10 enter the sections, elevating platforms in

the rear end of the machine for supporting the separate sections, a lowering platform in the forward end of the machine for receiving the assembled sections, a shaft mounted longitudinally of the machine for 20 the elevating platform, a shaft for the lowering platform, drums thereon cables around said drums extending down to one side of each platform, cables on said drums extending downwardly, thence across the 25 machine, thence upwardly, and thence down to the other side of each platform, and means for imparting rotation to the shafts.

Des Moines, Iowa, February 21, 1922.

DON L. HARFORD.
